UNITED STATES PATENT OFFICE

96,740

DESIGN FOR A COMBINED MINT AND NUT DISH

Ruth L. Gerth, New York, N. Y., assignor to The Chase Companies, Incorporated, Waterbury, Conn., a corporation

Application July 1, 1935, Serial No. 57,472

Term of patent 7 years

To all whom it may concern:

Be it known that I, Ruth L. Gerth, a citizen of the United States, residing at New York, in the county of New York and State of New York, have invented a new, original, and ornamental Design for a Combined Mint and Nut Dish, of which the following is a specification, reference being had to the accompanying drawing, forming part thereof.

Fig. 1 is a perspective view of a combined mint
and nut dish showing my new design;

Fig. 2 is a front view of the same; and

Fig. 3 is a plan view of the same.

I claim:

The ornamental design for a combined mint and nut dish substantially as shown.

RUTH L. GERTH.
